COMPACT, FOLDABLE AND DISPOSABLE BARBECUE GRILL

Frank L. Dale, 50 Riverside Drive,
New York, N.Y. 10024

Filed Feb. 13, 1967, Ser. No. 5,796

Term of patent 14 years

(Cl. D81—10)

FIG.1

FIG.5

FIG. 1 is a top plan view of a compact, foldable and disposable barbecue grill in folded position showing my new design;

FIG. 2 depicts a side elevational view thereof;

FIG. 3 is a bottom plan view of my grill, also in folded position;

FIG. 4 is a perspective view of the grill in open and set-up position showing my new design; illustrating the top, side and rear thereof; and

FIG. 5 is a front elevational view of the grill in open and set-up position.

I claim:

The ornamental design for a compact, foldable and disposable barbecue grill, as shown and described.
